OR D 13.154

13, 154.

Aug 8- 1882.

UNITED STATES PATENT OFFICE.

EDUARD LEISSNER, OF NEW YORK, N. Y.

DESIGN FOR WALL-PAPER.

SPECIFICATION forming part of Design No. 13,154, dated August 8, 1882.

Application filed June 30, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

The figure H is a vine bearing upon it leaves somewhat resembling oak-leaves. This vine H divides into three branches. The branch e

bears a large partly-open flower and a hanging bud. The branch f bears a similar flower not so widely open. The branch g, the continuation of which is marked G, bears a widely-open flower, d, and divides into the branch I, bearing the similar flower, e, and into the branch J, which again runs into the vine II. The background has branches resembling willow-branches scattered over it at intervals.

I claim—

The design for wall-paper, consisting of the figures II e f g d G I c J, substantially as shown.

EDUARD LEISSNER.
